UNITED STATES PATENT OFFICE.

HENRY S. JUDD, OF WILMETTE, ILLINOIS, ASSIGNOR TO JUDD LAUNDRY MACHINE COMPANY, OF WILMINGTON, DELAWARE, A CORPORATION OF DELAWARE.

WRINGER.

1,112,984.

Specification of Letters Patent.

Patented Oct. 6, 1914.

Application filed November 22, 1912. Serial No. 732,962.

To all whom it may concern:

Be it known that I, HENRY S. JUDD, a citizen of the United States, residing at Wilmette, in the county of Cook and State of Illinois, have invented a certain new and useful Improvement in Wringers, of which the following is a specification.

My invention relates to wringers, and the object of the invention is to provide a wringer so constructed that the pressure between the rollers may be instantly released in case the hand or clothing of the operator should be caught. I accomplish my object by the mechanism illustrated in the accompanying drawings, in which—

Figure 1 is a general front elevation of a wringer embodying my invention. Fig. 2 is an end view thereof, and Fig. 3 is a detail showing upon an enlarged scale that part 20 of the apparatus more particularly concerned with my invention.

Similar numerals refer to similar parts throughout the several views.

The wringer frame 1 supports the lower 25 roller 2 and upper roller 3, operated by gears 4 in the ordinary manner. These may be driven by power or by hand crank 5.

The upper roller is vertically movable, and in the preferred construction the upper 30 roller is journaled at the ends in blocks 6, which are vertically guided in slots 7 formed in the wringer frame. Springs 8 are mounted in the slots for holding the blocks 6 and upper roller down, as in the ordinary construction. At the top of the frame a cross bar 10 extends from one side to the other, entering the slots 7 above the springs. The purpose of this bar is to back up the springs, and in the preferred construction adjustment is provided for by screws 11 which coöperate with threaded blocks 12 located in the bar, the lower end of the screws abutting blocks 13 at the top of the springs, as shown in detail in Fig. 3. By screwing 45 the screws 11 up or down tension upon the springs may be increased or decreased.

The bar 10, instead of being fastened in the frame, is vertically movable therein, as above suggested, and is held down in position by detents 15. In this preferred construction the detents are yoke shaped and extend over the top or back of bar 10 and down the sides of the frames, to which they are pivoted by pins 16. The detents are 55 provided with handles 17 and the detents

are so placed at the ends of the bar that they may be readily rotated over the end of the bar out of engagement therewith.

In operation, the parts are assembled in the relative positions shown in the drawings, with the bar 10 backing up the springs and the detents in vertical position. The upward movement of the bar 10 is limited by the detents, and any degree of tension upon the springs may be obtained by means 60 of the adjusting screws 11. If by accident the clothing or fingers of the operator becomes caught in the rolls or a wad of clothing too large for the wringer is about to be dragged through, the operator may instantly release the tension of the springs by throwing one or both of the detents to non-acting position. It is not necessary to release both of the detents to release the pressure of the upper roller, partially at least, 65 and as the detents are located in a very accessible position and are operable from either side of the wringer and as there is a detent at each end of the wringer it is but the act of a moment to release one or both of 70 these detents.

It will be noted that as a result of my construction the cross bars may be instantly released for the purpose of renewing or repairing the rollers or other operating parts 85 of the wringer, and this may be accomplished without changing the adjustment of the screws. In other words, the parts may be disassembled and then reassembled without changing the original adjustment. 90

Having thus described my invention, what I claim as new and desire to secure by Letters Patent is:—

1. In a wringer, the combination of a frame provided with a pair of uprights, 95 one at each end of the frame, said uprights having vertical slots therein which are open at the top, a pair of rollers in said frame one of which is vertically movable, a spring in each of said uprights for holding the movable roller to its work, a vertically movable cross bar extending from one upright to the other located above and backing up said springs and having its ends extending into said slots whereby its movement is confined to a vertical path, and a yoke on each upright pivoted to the sides thereof and extending across the top of the upright across the slot therein for holding the cross bar down on said springs, said yokes being capa- 100

110

ble of swinging clear of the top of the uprights to thereby release either end of the horizontal bar.

2. In combination, a pair of wringer rollers, one above the other, the upper one being provided with bearing blocks at the ends, a wringer frame having two upright members at the ends, each provided with a vertical slot open at the top, said bearing blocks sliding vertically in said slots, compression springs overlying the movable blocks, a cross bar extending across from one upright to the other located above and into said slots and being vertically movable therein, adjusting screws carried by said bar and acting upon said springs, yokes

pivoted to the sides of the upright members and extending over the top thereof across the slots for holding the cross bar down, said yokes being capable of swinging outward to clear and release the cross bar at either end thereof, and an upstanding handle on each of said yokes for manipulating it.

In witness whereof, I have hereunto subscribed my name in the presence of two witnesses.

HENRY S. JUDD.
